UNITED STATES PATENT OFFICE.

WILLIAM RICHARD WHITE, OF BLOOMINGTON, ILLINOIS.

DESIGN FOR A GATE-HINGE.

SPECIFICATION forming part of Design No. 31,750, dated October 31, 1899.

Application filed October 2, 1899. Serial No. 732,416. Term of patent 14 years.

To all whom it may concern:

Be it known that I, WILLIAM RICHARD WHITE, a citizen of the United States, residing at Bloomington, McLean county, State of Illinois, have invented and produced a new and original Design for a Gate-Hinge, of which the following is a specification.

The accompanying drawing shows a perspective view of a hinge made in accordance with my design.

The leading feature of my design consists of two flat arms 1 and 2, which are joined together at one end and diverge at the other. One of the arms is straight throughout its length, and the other one is bent or angled at a point 3 intermediate its ends. The portion of the arm between the bend and the united end lies parallel with the straight arm, and

the other end of said bent arm has a substantially semicylindrical curve or eye 4 extending transversely of the length of the arm. The parallel portions of said arms are provided with registering perforations 5, and the remaining portion of the straight arm is provided with openings 6.

Having described my invention, I claim—

The design for a gate-hinge, substantially as herein shown and described.

In testimony whereof I have signed my name to this specification in the presence of two subscribing witnesses.

WILLIAM RICHARD WHITE.

Witnesses:

W. E. MAYNARD,
JAMES H. HENDRYX.
